Patented June 5, 1917.

UNITED STATES PATENT OFFICE.

ANDREW HANAUER, OF NEW YORK, N. Y.

SHADE-AWNING SUPPORT.

1,228,668.

Specification of Letters Patent.

Patented June 5, 1917.

Application filed January 12, 1917. Serial No. 141,940.

To all whom it may concern:

Be it known that I, ANDREW HANAUER, a subject of the Emperor of Austria, resident of New York, county of New York, and 5 State of New York, have invented certain new and useful Improvements in Shade-Awning Supports, of which the following is a specification.

This invention relates to improvements in 10 awning supports, and has as its principal object the provision of means which are readily attachable to windows of ordinary construction in such manner that the shade or curtain may be used as an awning extending exteriorly of the window.

Another object is to provide such means in 15 forms which are cheap to construct and easy to adjust, and which when in a folded position do not obstruct the window space.

20 These and other like objects are attained by the novel construction and combination of parts hereafter described and shown in the accompanying drawing, forming a material part of this specification, and in 25 which:—

Figure 1 is a vertical sectional view of a window showing the application of the invention, the awning being extended as in use.

30 Fig. 2 is a similar sectional view of the same, the parts being in a folded position, and

Fig. 3 is an enlarged perspective view showing the details of construction.

35 Fig. 1 of the drawing shows a window frame 10 with the lower and upper sashes respectively 11 and 12, both being in a raised position, and the curtain or shade 14 extended outwardly below the sashes and disposed at such an angle as to prevent the rays of sun from entering the window.

In Fig. 2, the sashes are shown in a closed position and the shade or curtain 14 partially raised on the inner side of the window.

40 45 Hingedly attached to the side frames 10 are arms 15 having secured at their outer ends bifurcated clips 16, adapted to contain in the openings 17, a stretcher stick 18 secured in the hem of the curtain, the stick being clamped within the openings 17 by the screws 19.

Also slidably engaged with the arms 15 are sleeves 20 having clamp screws 21 provided with a peculiar shaped head 22 for 50 reasons farther on described.

Near one end of the sleeve 20 are eyes or loops 25 and engaging therewith are similar loops 26, the latter being rigidly inserted near the ends of the bars 27 in such manner that the arms and bars are loosely but positively engaged. The outer opposite ends of the bars 27 are reduced in thickness and formed with hooks 28 adapted to engage with the necks 29 of the button-head studs 30 fixed in the window frames above the 60 point of attachment of the arms 15.

When it is desired to make use of the curtain as an awning, the arms 15 are extended horizontally, the bars 27 engaged with the studs 30 and the sleeves 20 adjusted along 70 the arms so as to maintain them either horizontally or at any desired angle. The curtain is then passed out through the window space below or above the open sashes, its weighted stiffening bar being disposed between the jaws of the clips 16 and secured by set screws as indicated.

If more light be desired, obviously the sleeves 20 will be moved outward toward the end of the arms, thereby raising them to 80 any desired degree.

When it is not desired to use the curtain as an awning, the parts are turned upward so as to bring the arms 15 into a substantially perpendicular position, the bars 27 being 85 turned sidewise upon the eye loops 25 and 26 so as to fold closely against the arms hanging pendent and engaged with the clips 32, and the hooked heads 22 engaged with the studs 30 thereby holding the device out 90 of the way.

I claim:—

1. An awning support comprising a pair of arms pivotally engaged with a window casing, open jawed members rigidly secured 95 at the outer ends of said arms, said members being receptive of the end of a curtain, means for clamping the curtain therein, sleeves slidably engaged on said arms, means for clamping said sleeves thereon, said clamp 100 means having a hooked head, a loop secured in each of said sleeves, a pair of support rods, other loops secured therein engaged with the first of said loops, hooks formed with the opposite end of said support rods, 105 and studs set in a window casing with which said hooks or screw heads are engageable.

2. An awning support comprising a pair of arms hingedly engaged at opposite sides of a window frame, means for detachably 110

engaging the hem of a curtain with the free end of said arms, sleeves operable on said arms, means for clamping said sleeve in an adjusted position, rods loosely hinged to said sleeves, means formed at the outer end of said rods for engaging with the window frame, and means for holding said arms and

rods parallel in a vertical position when in a folded position, said means being formed with said sleeve clamping means.

10

In testimony whereof I have affixed my signature this 2nd day of January, 1917.

ANDREW HANAUER.
